THREAD-CONTROLLING MECHANISM.

1,275,999.

Specification of Letters Patent. Patented Aug. 20, 1918.

Application filed June 30, 1916. Serial No. 106,761.

To all whom it may concern:

Be it known that we, EDWARD B. ALLEN and BENJAMIN F. CROSBY, respectively a citizen of the United States and a subject 5 of the King of Great Britain, both residing at Bridgeport, in the county of Fairfield and State of Connecticut, have invented certain new and useful Improvements in Thread-Controlling Mechanism, of which the following is a specification, reference being had 10 therein to the accompanying drawings.

This invention relates to overseaming stitch-forming mechanism in which means are provided for coöperation with a reciprocating needle for concatenation of thread-loops above and below the work; and it has 15 for its object to insure the initial concatenation of such thread-loops below the work in beginning the stitching period. If the 20 initial concatenation of thread-loops at the beginning of a seam were effected above the fabric, an objectionable loose thread would be left upon its face and the first stitch of a series would be loosely made. It is accord- 25 ingly the object of the present invention to so begin a seam that the end of such thread will be invariably attached initially below the fabric.

While the present improvement is not 30 limited to employment in connection with any particular variety of stitch-forming mechanism of the type described, it is designed particularly for application to mechanism comprising a reciprocating thread- 35 carrying needle and coöperating lower-thread loop-taking means including a looper adapted to seize and spread needle-thread loops below the work and an overedge thread-carrying loop-presenting needle or 40 element adapted to carry its thread through the needle-thread loop so spread and present a loop of its own thread above the work for passage of the needle in its succeeding thrust. To insure the proper presentation 45 of the lower-thread loop, the overedge needle in the initial portion of its descending or retractive movement has a dwell involving a slight reversal of such initial movement so as to allow ample time for passage of the 50 upper needle through the loop of lower thread thus formed.

The present invention consists in means

adapted to act during an initial thrust only of the needle to prevent seizure of a thread-loop from the loop-presenting element. This 55 result is preferably accomplished by providing means for maintaining the lower thread taut when its respective loop-presenting element is in loop-presenting position in the initial stitch-forming cycle of a series and 60 for insuring the proper formation of lower-thread loops at the corresponding stages of the succeeding cycles of the series.

In its preferred embodiment, the invention is applied to a buttonhole machine construct- 65 ed in substantial accordance with that of the United States patent to Edward B. Allen, No. 1,162,207, dated November 30, 1915, and comprises a thread-drawing or slack-thread controlling lever adapted for en- 70 gagement with the lower thread at a point between the usual fixed thread-end clamp upon the traveling work-holder and an intermittently acting thread-nipper with actuating means whereby it is closed upon the 75 lower thread while the upper needle is passing through the lower-thread loop above the work. The rotary looper-actuating shaft preferably carries a controlling cam acting upon the thread-drawing lever constituting 80 a loop-robbing device which is normally maintained in retracted and inactive position by a latch or detent adapted to be released, in the machine referred to, by en- 85 gagement of a tappet-arm carried by the traveling cutting device in a buttonhole cutting operation preceding each stitching operation.

In the accompanying drawings, Figure 1 is a rear side elevation of a portion of the 90 said buttonhole machine provided with the present improvement, and Fig. 2 a front end view of the same with the detachable forward portion of the base omitted. Fig. 3 is a perspective view of the parts represent- 95 ed in the preceding figures, portions of which are represented in dotted lines. Fig. 4 is an elevation of a portion of the lower-thread loop-presenting needle and its actuating means. Fig. 5 is a perspective view of the 100 thread-nipping device and its carrier-plate and Fig. 6 a transverse section of the same upon a larger scale. Fig. 7 is a perspective view of the thread-drawing lever and its

latch, and Figs. 8, 9, 10 and 11 are perspective views representing parts of the actuating means for the loop-taking devices. Fig. 12 is a perspective view representing the upper 5 per needle and the coöperating loop-presenting element under the action of the loop-robbing device.

The machine is represented with the usual hollow rectangular base 1 from the rear end 10 of which rises the hollow standard 2 of the bracket-arm. Journaled within and longitudinally of the base is the main-shaft 3 carrying at its rearward end the loose belt-wheel 4 adapted for detachable connection with the 15 main-shaft by means of a stop-motion comprising the clutch-ring 5 adapted for engagement by the spring-pressed tooth 6 of the swinging stop-lever 7 mounted upon the rock-shaft 8 which is journaled in the 20 bracket 9 sustained by the base 1. The stop-motion acts as usual to control the period of operation of the main-shaft 3, and hence of the stitch-forming mechanism which comprises the reciprocating eye-pointed upper 25 needle *n*, the loop-seizing element or looper *l* and the eye-pointed lower-thread-loop presenting needle or element *t*.

As represented in the accompanying drawings, the looper mechanism is substantially 30 the same as that of the said Patent No. 1,162,207. The main-shaft 3 has secured upon its forward end, as represented in dotted lines in Fig. 1, the gear-wheel 10 meshing with the toothed pinion 11 upon 35 the rearward end of the looper-actuating shaft 12 journaled in bearings sustained by the cross-member 13 of the base 1 and carrying upon its forward end the crank 14. The crank 14 is connected by means of the link 40 15 with a stud-pin 16 carried by the swinging lever 17 having its hub 18 fulcrumed upon the stud-screw 19 which is sustained upon the frame member 13.

The lever 17 is connected at its free end 45 by means of the link 20 with the stud-screw 21 carried by the plunger-rod 22 suitably journaled in the frame and provided with a lateral arm 23 forked at its outer end to enter the annular notch or neck 24 formed 50 in the lower end of the tubular plunger-rod 25.

The rod 25 is slidingly journaled within a bearing boss 26 depending from the rotary turret 27 which is journaled within a suitable bearing of the curb 28 sustained by the frame member 13, and is provided with a laterally extending head 29 apertured at its outer end to fit the guide-post 30 adjacent which it is connected by means of the 55 link 31 with the swinging lower-needle carrier-arm 32 fulcrumed at 33 upon the supporting post 34 mounted upon the carrier 27. The head 29 of the rod 25 is apertured to fit the spiral gear 35 operatively connected with the rocking and bodily-recipro- 60

cating carrier 36 for the looper *l*. The upper and lower needles operate as usual through a needle-throat 37 sustained by a bracket 38 carried by the turret 27.

In the mechanism as thus described, the 70 swinging lever 17 and link 20 constitute a toggle connection between the looper-actuating shaft and the looping elements co-operating with the needle. The movement of the toggle beyond straightened position, 75 as represented in Fig. 2, causes a dip or "reaction" of the lower-needle or loop-presenting element *t* in the upper portion of its stroke to form and sustain a lower-thread loop in position for the upper needle *n* to 80 pass through it, the lower-thread loop having entered a loop of upper thread seized from the needle by the looper *l* and distended for passage of the lower needle *t*.

Suitably sustained by the cross-member 13 85 is a bracket-plate 39 having secured thereto the block 40 formed with a vertical socket 41 in which is journaled the shouldered plunger-rod 42 whose reduced and threaded upper portion projects above said bearing 90 block and carries the adjustable thread-nipping disk 43. The upper end of the block 40 affords the fixed element of a nipping device of which the movable element is the disk 43, which is normally pressed upon 95 the fixed element by means of a spring 44 embracing the reduced portion of the rod 42 between the shoulder of which and the opposite end of the socket 41 it is interposed. The rod 42 carries a lateral stud 45 passing 100 through a slot 46 in the bearing block 40 by which the endwise movements of the rod 42 are limited.

The rod 42 has secured in its lower end the contact-screw 47 which is adjustably 105 secured in position by means of a lock-nut 48. The head of the contact screw 47 is adapted for engagement by one arm of a rock-lever 49 fulcrumed intermediate its ends upon the stud-screw 50 tapped into an 110 extension of the member 13 and having its opposite end resting against a cam-element 18' afforded by the flattened lower side of the hub 18 of the swinging lever 17 by the operative movements of which the rock-lever 49 is operated to lift the plunger-rod 115 42 in each stitch-forming cycle to permit the measuring off of a supply of lower thread for the succeeding stitch, the thread-nipper remaining closed at other times under the 120 action of the spring 44.

Secured to the bracket-plate 39 by means of the shouldered tension stud 51 is the plate 52 carrying the lateral thread guide-pin 53 adjacent which is the clearance slot 54 extending from its lower edge. The plate 52 is provided at its outer end with a lateral lip 55 at the base of which is the thread slot 56 having at its upper end the threading slit 57. To the tension stud 51 are ap- 125 130

plied the tension-disks 58 pressed together and upon the plate 52 by means of the spring 59 interposed between the outer tension-disk and the nut 60 applied to the outer 5 threaded portion of the stud 51. In threading the machine, the lower thread *s* is passed through an aperture 61 in the side of the base 1 (Fig. 3) through the eye in the guide-plate 61' secured to the block 40 and between 10 the nipping elements 40 and 43 and the tension disks 58, thence over the guide-pin 53 and through the thread-slot 56 from which it is led upwardly through the tubular rod 25 to the lower needle or loop-presenting element *t* and thence beneath the usual thread-clamping spring-plate 62 secured by means 15 of the screw 62' upon one of the work-holding clamp-plates 63.

Rigidly secured to the lateral arm 23 of the rod 22 is the pull-off arm 64 provided at its outer end with an outwardly extending finger 64' normally disposed below the thread aperture of the plate 61', but adapted to be moved upwardly, as represented in 25 Figs. 2 and 3, to draw thread from the lower-thread supply while the nipping elements are closed upon the thread.

Mounted upon a shouldered stud 65 sustained by the member 13 is an angle-lever 30 having a lateral arm 66 and an upwardly extending arm 67, the latter being formed with an angular pawl-shaped extremity. To the lateral arm of this lever is adjustably secured by means of the screw 68 an 35 angular thread-engaging arm 69 having an inwardly extending finger 69' movable, when the arm 66 rises, into the clearance slot 54. The lever-arm 66 is normally pressed downwardly by means of the spring 40 70 coiled around the hub 66' of the angle-lever and connected at its opposite ends respectively with said lever and the frame-member 13.

The thread-engaging arm 69 is normally 45 maintained in upper inoperative position with the finger 69' within the slot 54 above the thread *s* by means of a pawl or detent-arm 71 fulcrumed upon a fixed stud-screw 72 and having near its outer end a notch 50 fording a shoulder 73 which is inclined downwardly and backwardly and therefore at an angle with the direction of movement of the detent-arm. When the pawl is disengaged from the upper extremity of the 55 lever-arm 67, the rounded free end of the arm 66 is maintained, under the action of the spring 70, in contact with the controlling cam 74 carried upon the outer face of the crank 14.

60 As represented in Fig. 2, the cam 74 has a nearly semi-circular portion concentric with the looper-actuating shaft 12 and an opposite flattened portion disposed nearly diametrically of said shaft. The point of the 65 arm 67 normally rests at the base of the

shoulder 73, in which position the arm 66 is maintained slightly retracted from contact with the concentric portion of the cam 74.

The lifting of the detent 71 while the initial end of the eccentric portion of the cam is presented to the lever-arm 66 permits the latter to contact with the same and to descend in its continued contact with the eccentric portion of the cam as the shaft 12 performs its initial rotation, thereby causing the thread-finger 69' to descend, as represented in Figs. 2 and 3, to draw thread between the nipper and the loop-presenting element *t*. As the outer portion of the arm 66 resumes engagement with the circular portion of the cam, the angle-lever is rocked to lift the thread-finger 69' above the guide-finger 53 and the point of the arm 67 engages the lower portion of the inclined shoulder 73 by which it is forced backwardly 80 slightly in the descent of the detent-arm 71 under the action of its spring 75 which is coiled around the stud 72 and has its extremities connected respectively with the arm 71 and a fixed part of the machine 85 frame. By this means the arm 66 is returned to retracted position slightly above the concentric portion of the cam 74.

Journalized in bearings 76 above the base 1 and extending crosswise of the standard 2 is 90 the cutter-actuating shaft 77 having loosely mounted thereon the grooved driving pulley 78 adapted to be set in driving relation with said shaft for production of a single rotation thereof at a time by means set forth 100 in the United States patent to E. B. Allen No. 1,048,786, of December 31, 1912. Fixed upon the cross-shaft 77 are the cutter-actuating cams, including the cam-disk 79 which is formed with the cam-groove 80 entered 105 by a stud 81 upon the link-bar 82 which is slotted in one end portion to embrace a guide-block fitted upon the shaft. At its opposite end, the bar 82 is adjustably connected by means of the bolt 83 with an extension of one of the standing lugs 84 of the fulcrum-sustaining slide-plate 85 slidably mounted upon the bed of the machine and carrying the fulcrum-pin 86 (Fig. 3) for the upper and lower cutter-levers 87 and 88 which are provided respectively with the buttonhole cutter 89 and the cutter-plate or anvil 90.

The slide-plate 85 is shown formed with a depending lug 91 carrying a block 92 to 110 which is secured by screws 93 the downwardly extending arm 94 terminating in a forwardly projecting tappet-finger 95 whose outer portion normally extends beneath the outer end of the latch-arm 71.

The upper or operative edge of the finger 95 is slightly inclined forwardly and downwardly, so that in its movement with the fulcrum-plate in carrying the cutting members from normal retracted position into op- 115 120 125

erative or cutting position, the latch-arm 71 is lifted. This permits the point of the lever-arm 66 to move laterally under the action of its spring 70 slightly beyond the 5 detent-shoulder 73, as represented in Fig. 3, to maintain the detent-arm 71 out of latching relation with the lever-arm 67.

The cam 74 at this time presents to the lever-arm 66 the initial end of the eccentric 10 portion of the cam 74 just beyond the termination of the concentric portion, and in the initial rotation of the controlling cam, the thread-drawing finger 69' descends to its lowest position so as to insure maintenance 15 of the lower thread taut at the stage of the stitch-forming cycle wherein the point of the upper needle passes the blade of the lower needle or loop-presenting element. The finger 69' thereafter quickly rises to 20 upper retracted position wherein it is held by engagement of the detent-arm 71 with the lever-arm 67.

Preparatory to a buttonhole producing operation, the cutter-levers 87 and 88 are 25 retracted from operative position and the cutting elements 89 and 90 are separated. The toggle device 17, 20, being bent to extreme position, the lower needle is in its lower position while the upper needle is 30 above the work-holder for insertion of the work.

Upon starting the machine, the cutting device advances for cutting a buttonhole slit and the tappet-arm 94 at the same time lifts 35 the detent-arm 71 for release of the thread-drawing element 66. Upon the retraction of the cutting device and the starting of the stitch-forming mechanism, the lower needle rises through the buttonhole slit and performs 40 its initial retractive movement followed by a dwell in loop-presenting position, at which time the action of the thread-drawing lever-arm 66 causes the lower thread leading from the eye of the lower needle through the buttonhole slit to remain taut, thereby causing the point of the upper 45 needle to pass at the outer side of the lower thread thus positioned, as represented in Fig. 12. During the rise of the upper needle 50 the thread-nipper 40, 43, is closed upon the lower thread, the pull-off element 64 rises to draw off a new supply of lower thread and the thread-drawing element 66 begins its descent to draw up the thread extending 55 from the nipper through the needle to the thread-clamp 62.

As the upper needle begins its rise from extreme lower position, a thread-loop is seized therefrom by the looper 7 and spread 60 for passage of the lower needle in its succeeding rising movement to present a loop of its thread for passage of the upper needle, the thread-drawing element 66 being meanwhile returned under the action of the cam 65 74 and the detent shoulder 73 to extreme

upper position in which it is maintained for the remainder of the buttonhole producing operation. An initial upper-thread loop having thus been seized below the work and locked by subsequent passage of the succeeding 70 lower-thread loop, the stitching now proceeds in the ordinary manner to the end of the stitching period. Thus the first concatenation of a lower-thread loop with the upper thread occurs below the fabric from 75 which the loose end of lower thread consequently extends, with the result that the first stitch upon the upper face of the fabric is firmly set and is not left in unfinished condition. 80

While the present improvement is herein shown and described as embodied in a buttonhole machine comprising a traveling cutting device and plural-thread stitch-forming mechanism, it is evident that it is readily 85 adapted to machines containing stitch-forming mechanism employing one or more threads wherein means are provided for co-operation with the needle both above and below the work, and that the means which 90 may be employed for setting the loop-robbing device in operation will be dependent upon the nature of the machine to which the device is applied. 95

Having thus set forth the nature of the invention, what we claim herein is:—

1. In a sewing machine, the combination with overseaming stitch-forming mechanism including a reciprocating needle and a loop-presenting element coöperating therewith for concatenation of thread-loops at opposite sides of the work, of means for preventing seizure of a thread-loop by the needle during its initial thrust at the beginning of a stitching operation, whereby to 100 secure the initial concatenation of thread-loops at the underside of the work. 105

2. In a sewing machine, the combination with overseaming stitch-forming mechanism including a reciprocating upper-thread-carrying needle and a lower-thread-carrying element coöperating therewith for concatenation of thread-loops alternately at opposite sides of the work, of a lower-thread-engaging device for preventing seizure of a 110 lower-thread-loop by the needle during its initial thrust at the beginning of a stitching operation, whereby to secure the initial concatenation of thread-loops at the lower side of the work. 115

3. In a sewing machine, in combination, stitch-forming mechanism comprising a reciprocating needle and a coöperating loop-presenting element, means acting, during an initial thrust only of said needle for seizure 125 of a thread-loop from said loop-presenting element, to prevent the seizure of said loop, but ineffective to perform such function in a succession of needle-thrusts thereafter.

4. In a sewing machine, in combination, 130

- stitch-forming mechanism comprising a reciprocating needle and a coöperating thread-carrying loop-presenting element, means acting, during an initial thrust only of said 5 needle for seizure of a thread-loop from said loop-presenting element, to prevent the seizure of said loop, but ineffective to perform such function in a succession of needle-thrusts thereafter.
- 10 5. In a sewing machine, in combination, stitch-forming mechanism comprising a reciprocating needle and a coöperating thread-carrying loop-presenting element, a thread-drawing element acting upon the thread carried by said loop-presenting element, and means for insuring a single actuation only of said thread-drawing element for maintaining said thread taut during a loop-seizing thrust of said needle at the beginning 20 of a series of stitches.
6. In a sewing machine, in combination, stitch-forming mechanism comprising a reciprocating needle and a coöperating thread-carrying loop-presenting element, a thread-drawing element acting upon the thread carried by said loop-presenting element, actuating means for said thread-drawing element, and controlling means for insuring the action of said actuating means in an initial 25 stitch-forming cycle of a series and for preventing its operation immediately before and after said initial stitch-forming cycle.
7. In a sewing machine, in combination, stitch-forming mechanism comprising a reciprocating needle and a coöperating loop-presenting element, spaced thread-clamping means acting upon a section of the thread of said loop-presenting element at opposite sides of the latter, and means whereby said 30 section of thread is maintained taut in the loop-presenting stage of an initial stitch-forming cycle of a series but is allowed to become slackened for seizure of the thread-loop in the next succeeding cycle.
- 40 8. In a sewing machine, in combination, stitch-forming mechanism comprising a reciprocating needle and a coöperating loop-presenting element, spaced thread-clamping means acting upon the thread of said loop-presenting element at opposite sides of the latter, and loop-preventing thread-drawing means acting upon said thread between one of said thread-clamping means and the loop-presenting element during the needle-thrust 45 of an initial stitch-forming cycle of a series and inactive thereon during the needle-thrust next succeeding the same.
9. In a sewing machine, in combination, stitch-forming mechanism comprising a reciprocating needle and a coöperating loop-presenting element with means for imparting thereto reciprocating movements with a dwell while in loop-presenting position, means acting upon the thread carried by 50 said element during the dwell of the latter in an initial stitch-forming cycle to maintain the thread taut while permitting the slackening of the thread at the same stage of the stitch-forming cycle next succeeding.
10. In a sewing machine, in combination, 70 stitch-forming mechanism comprising a reciprocating needle and a coöperating loop-presenting element, and an automatically acting thread-nipper acting upon the thread of said loop-presenting element, of a normally inactive thread-drawing element for said thread disposed between the loop-presenting element and the thread-nipper, and means for actuating said thread-drawing element while the loop-presenting element is in loop-presenting relation with the needle and while the nipper is closed upon the thread.
11. In a sewing machine, in combination, 75 stitch-forming mechanism comprising a reciprocating needle and a coöperating loop-presenting element, of a thread-drawing element adapted to act upon the thread carried by said loop-presenting element, and controlling means for insuring the action 80 of said thread-drawing element upon the thread while said loop-presenting element is in loop-presenting relation with the needle in an initial stitch-forming cycle and its inaction upon the thread in the corresponding 85 stages of a succession of stitch-forming cycles next succeeding said initial stitch-forming cycle.
12. In a sewing machine, in combination, 90 stitch-forming mechanism comprising a reciprocating needle and a coöperating loop-presenting element, of a normally inactive thread-drawing element adapted to act upon the thread carried by said loop-presenting element, and controlling means 95 for insuring the action of said thread-drawing element upon the thread while said loop-presenting element is in loop-presenting relation with the needle in an initial stitch-forming cycle and its inaction upon the thread in the corresponding 100 stages of a succession of stitch-forming cycles next succeeding said initial stitch-forming cycle.
13. In a sewing machine, in combination, 105 stitch-forming mechanism comprising a reciprocating needle and a coöperating loop-presenting element, of a spring-actuated thread-drawing element adapted to act upon the thread carried by said loop-presenting element, a detent for maintaining 110 said thread-drawing element normally inactive, means acting preparatory to a stitching period for tripping said detent to release said thread-drawing element, and controlling means acting within an initial 115 stitch-forming cycle to permit an operative movement of the thread-drawing element and to thereafter restore to it normal relation with said detent before the completion 120 of the next succeeding stitch-forming cycle.
- 125 130

14. In a sewing machine, in combination, a stitch-forming mechanism comprising a reciprocating needle and a co-operating loop-presenting element, of a spring-actuated thread-drawing element adapted when released to draw upon the thread carried by said loop-presenting element, controlling means operative during a stitching period for causing reciprocal thread-drawing and retractive movements of said thread-drawing element, a detent comprising means for normally retracting and holding said thread-drawing element out of contact relation with said controlling means, and tripping means for said detent. 65
15. In a sewing machine, in combination, a stitch-forming mechanism comprising a reciprocating needle and a co-operating loop-presenting element, a spring-actuated thread-drawing element adapted to act upon the thread carried by said loop-presenting element, controlling means operative during a stitching period for causing reciprocal thread-drawing and retractive movements of said thread-drawing element, a reciprocating detent provided with a detaining shoulder inclined to its direction of movement and adapted for engagement with a part of said thread-drawing element, and tripping means for said detent. 70
16. In a buttonhole sewing machine, in combination, a stitch-forming mechanism comprising a reciprocating needle and a co-operating loop-presenting element, and a buttonhole cutting mechanism, means acting, during an initial thrust only of said needle for seizing a thread-loop from said loop-presenting element, to prevent the seizure of said loop, but ineffective to perform such function in a succession of needle thrusts thereafter, and means operatively connected with said cutting mechanism for setting the first-named means in action. 75
17. In a buttonhole sewing machine, in combination, a stitch-forming mechanism comprising a reciprocating needle and a co-operating loop-presenting element, and a buttonhole cutting mechanism, a normally inactive thread-drawing element, means operative within a stitching period for actuating the same, and means under the control of the cutting mechanism for setting the same in action. 80
18. In a buttonhole sewing machine, in combination, a stitch-forming mechanism comprising a reciprocating needle and a co-operating loop-presenting element, a spring-actuated thread-drawing element adapted to act upon the thread carried by said loop-presenting element, a detent for maintaining said thread-drawing element normally inactive, tripping means for said detent with means for actuating the same intermediate stitch-forming periods, and means for restoring said thread-drawing element to engagement with said detent after a single thread-drawing action thereof succeeding the tripping of said detent. 85
19. In a buttonhole sewing machine, in combination, a stitch-forming mechanism comprising a reciprocating needle and a co-operating loop-presenting element, and a buttonhole cutting mechanism, a spring-actuated thread-drawing element adapted to act upon the thread carried by said loop-presenting element, a detent for maintaining said thread-drawing element normally inactive, means connected with the buttonhole cutting mechanism for tripping said detent to release said thread-drawing element, and controlling means for insuring the operation of said thread-drawing element in one stitch-forming cycle and its return to normal relation with the detent in a succeeding stitch-forming cycle. 90
20. In a buttonhole sewing machine, in combination, a stitch-forming mechanism comprising a reciprocating needle and a co-operating loop-presenting element, and a traveling buttonhole cutting device movable toward and from the stitch-forming mechanism, a spring-actuated thread-drawing element adapted to act upon the thread carried by said loop-presenting element, controlling means for insuring thread-drawing and retractive movements of said thread-drawing element within a stitch-forming period, a detent for maintaining said thread-drawing element normally in retracted position, and tripping means for said detent carried by and partaking of the traveling movements of said cutting device. 95
21. In a sewing machine, the combination with a reciprocating needle a thread-carrying loop-presenting element and actuating means for said element including a toggle device, of a nipping device for the thread of said loop-presenting element, and operating means therefor including means connected with and operated by said toggle device. 100
22. In a sewing machine, the combination with a thread-carrying loop-presenting element and actuating means therefor including a toggle device with a cam-element formed upon one of its component members, of a nipping device for the thread of said loop-presenting element, and a rock-lever operatively connected with said nipping device and deriving operative movements from said cam-element. 105
23. In a sewing machine, the combination with a looper mechanism comprising a toggle device, of an intermittently acting thread-nipping device, a thread-guide spaced therefrom, a pull-off member movable intermediate said nipping device and thread-guide, and means including independent connec- 110
- 120
- 125

tions with said toggle device for imparting operative movements to said nipping device and pull-off member.

24. In a sewing machine, the combination with looper mechanism comprising a toggle device and a reciprocating rod actuated thereby, of an intermittently acting thread-nipping device, a thread-guide spaced therefrom, and a pull-off member movable intermediate said nipping device and thread-guide and deriving operative movements from said reciprocating rod.

25. In a sewing machine, the combination with looper mechanism including a toggle device with a cam-element formed upon

one of its component members and a reciprocating rod deriving operative movements from said toggle device, of an intermittently acting thread-nipping device, an operative connection between the nipping device and said cam-element, a thread-guide spaced from said nipping device, and a pull-off member movable intermediate said nipping device and thread-guide and deriving operative movements from said reciprocating rod. 20 25

In testimony whereof, we have signed our names to this specification.

EDWARD B. ALLEN.
